**PIPE LINE FOR CONVEYING SULFUR AND
OTHER HOT LIQUIDS**

Clarence O. Lee and Clifford M. Cockrell, New Orleans, La., assignors to Freeport Sulphur Company, New York, N.Y., a corporation of Delaware
Filed July 1, 1959, Ser. No. 824,245
6 Claims. (Cl. 165—81)

The present invention relates to the transportation of hot liquids and, more particularly, to an improved composite pipeline and method for transporting hot liquids underground or under water for long distances of several miles or more. The materials which can be transported in this manner are those which are solid or viscous in their natural state but are free-flowing liquids when heated, such as sulfur, asphalt, heavy molasses and the like.

The mining of sulfur is economically achieved by changing it from a solid to a liquid at its source in the mine, and conveying the molten sulfur under pressure through a conduit leading from the mine to ground level. While this method may present some problems where the sulfur mine is beneath dry land and no substantial overland transportation is necessary, serious problems arise when the mine is beneath the sea, requiring transportation of the molten sulfur long distances to shore.

One of the principal objects of this invention is to provide a method of, and apparatus for mining a solid material capable of being melted by the application of heat and for transporting the material over great distances in a molten state.

Another principal object of this invention is to provide a method of, and apparatus for mining sulfur at sea and transporting the sulfur to the shore.

Another object of this invention is to provide such a system in which the material to be mined is changed to a liquid at its source and forced under pressure through a conduit buried beneath the ground or sea floor while maintaining the material in a liquid state.

Another object of this invention is to provide such a system in which the buried conduit is a composite pipe-line and includes no expansion joints.

Another object of the invention is to provide such a system including a mining station or a mining platform at sea at which mining equipment is provided and a prestressed, composite piping arrangement extending from the platform or station to a distant destination.

Another object of this invention is to provide such a system wherein the prestressed piping arrangement is buried beneath the ground or sea floor from a point adjacent the platform or station to a distant destination.

Another object of this invention is to provide such a system wherein the prestressed condition of the composite piping arrangement is substantially relieved during the normal functioning of the system.

Although the principles of the invention are equally applicable to the mining of meltable material and transporting it great distances over dry land or land incapable of accommodating surface transportation, they will be shown and described as applied to a system for mining such a material as sulfur, where the sulfur dome is beneath a large body of water and at a great distance from shore.

In one aspect of the invention, an outer or main casing, adapted to contain a line for conveying the molten material and an insulated jacket line surrounding the latter for conveying water or other heating fluid, may be fabricated on shore in sections with or without the material-conveying and jacket lines therein. Each section may have two parallel sections of water line attached on opposite sides of the casing section in a manner to provide a multi-line section of piping having a relatively wide bottom

2

surface area for adequately supporting the piping arrangement within the soil at the sea bottom.

The three portions of each composite section may be welded to succeeding sections on shore, and the initial sections may be attached to a vessel (or barge) so that the pipeline is pulled out to sea as succeeding sections of the composite line are welded together. The assembled line may be pulled out to sea until the initial section is spaced from a mining platform by an amount substantially equal to the thermal strain to which the casing will be subjected during normal operation, or by an amount 50 to 70% thereof.

A sea-station or platform may be provided containing mechanism for prestressing the main or outer casing by subjecting it to a tensile stress sufficient to strain the main casing until it reaches the platform or mining location. This may be done by providing anchors, suitably of temporary nature, from which chains extend to sheaves attached to the offshore end of the main casing, thence vertically upwardly to the sea-station. The sea-station may extend from the mining platform to the offshore end of the main casing and include a hydraulic jack mechanism mounted on sliding guide ways. With the shore end of the casing securely anchored, the ends of the chains opposite those connected to the seaward anchors may be raised by the jacking mechanism thereby applying an axial strain to the main outer casing, causing it to be stretched to the sea-station. Alternatively, the mechanism and power for prestressing may be situated on shore or on a barge operating in conjunction with anchors and cables.

After the main casing is prestressed, it is buried to a predetermined depth below the sea bottom. Not only will this insulate the casing against excessive heat losses, but when the back fill has developed sufficient shearing strength, such casing will remain prestressed after the prestressing mechanism is removed or the anchor-forming part of the tensile stressing apparatus and the shore anchor are disconnected.

In another aspect of the invention, the insulated hot fluid conveying line that surrounds the molten material conveying line within the main casing has mounted at each quadrant and externally thereof a series of rollers or other antifriction means for facilitating its movement axially of the main casing during assembly, during temperature changes of normal use and during replacement.

The material-conveying line may be provided with radial pins at each of two quadrants externally thereof for the purpose of spacing the material-conveying line eccentrically within the hot water line, providing means for controlling buckling of the material-conveying line when in compression. Succeeding sections of these two lines may be welded on shore and guided into the trailing or shore end of the previously laid main casing or into each section of the main casing before it is laid. The roller means on the outer periphery of the hot fluid line may be located at periodic intervals along the assembled lines, thereby facilitating the movement of the two lines within the main casing.

In another aspect of the invention, the material-conveying and hot water lines when first assembled, may extend into the main casing to a point short of the end of the main casing. When the system is employed with sulfur, it will be subjected to a temperature of about 300° F. because, although the melting point of sulfur is only 240° F., its lowest viscosity occurs at about 300° F. and becomes excessive above 320° F. Accordingly, the sulfur may enter the sulfur line at 320° F. at the mine and drop to about 280° F. at the shore or destination end of the line. In order to minimize stresses due to the elevated operating temperatures, during assembly, water may be circulated in these two lines within the main casing at a predetermined temperature, causing them to expand a predetermined

mined amount depending upon the prestress desired. These two interior lines may then be attached at each end to the main casing forming a composite prestressed arrangement. The main casing may be prestressed in tension to about 10,000 p.s.i. and the hot water and sulfur lines may be prestressed to any value up to their yield strength. These values are merely exemplary and comprise one set of satisfactory functioning conditions. Accordingly, when the lines go into operation at their higher operating temperatures, the main casing will have its tensile stress substantially relieved, while the hot fluid and sulfur lines will go into compression to a figure somewhat below their yield strength.

The above as well as other objects and novel features of the invention will become apparent from the following specification and accompanying drawings which are merely exemplary.

In the drawings:

FIG. 1 is a schematic diagram of a mining and transporting system of the invention;

FIG. 2 is a sectional elevational view of the multiline system taken substantially along line 2—2 of FIG. 1;

FIG. 3 is a section of the main casing and the internal pipe lines therein, of FIG. 2;

FIG. 4 is an elevational view of a prestressing apparatus which can be employed in performing a portion of the method of the invention;

FIG. 5 is a detail of the apparatus of FIG. 4; and

FIG. 6 is another detail of the apparatus of FIG. 4.

Referring to FIG. 1, a multi-pipe system 10 is laid along and in a trench 11 cut in the soil under the sea or other large body of water 12. Alternatively, the pipe system may be laid on the surface of the sea bottom and then buried by the action of a water jet and gravity. Referring to FIG. 2, this composite piping system includes an outer casing 13 of steel, which may be an A.P.I. 5L line pipe having a yield strength of 42,000 p.s.i. and may be provided with a protective corrosive resistant coating 14 about its outer surface. The casing 13 may be made up of random length sections having bell and spigot connections 15 (FIG. 3) at its ends forming means whereby succeeding sections may be welded together. Alternatively, the pipes may have butt ends over which sleeves may be welded. With either of these constructions, the joints are free of internal humps or projections. Inside the casing 13, an insulated jacket line 17 may be located axially of the casing 13. The line 17 may be made of a high tensile steel having a yield strength of 25,000 to 90,000 p.s.i. It preferably has a relatively thick insulation coating 18 around its outer surface, preferably composed of a non-rigid insulating material 18 having a relatively low thermal conductivity factor, such as bonded glass, mineral wool, asbestos, foam glass, insulating concrete, calcium silicate or the like.

Under the steel supporting bands 19, located at periodic intervals along the jacket line 17 there is, preferably, a rigid insulation material of high strength, such as calcium silicate. If a non-rigid insulation material were used under these bands, these bands would have to be rigidly secured to the pipe 17 through a rigid intermediate element. Each quadrant of the supporting bands 19 may be provided with openings 20 therein for the reception of roller units 21 or other antifriction means. The roller units 21 in each quadrant tend to prevent contact between the inner surface of the outer casing 13 and either the bands or the insulation coating. The roller units 21 may be aligned and spaced apart sufficiently to straddle the bell and spigot joints 15 at the ends of the sections of the main casing 13. Each roller unit 21 may include a plate 22 having a box-like housing 23 of rectangular shape. Rollers 24 may be trunnioned in the sidewalls of the housing 23, and the plates may be welded or otherwise fastened to the supporting bands 19. Two rollers are preferably placed in tandem in each band spaced such that when one roller passes over the annular groove left

5 at the joint, the other roller will support the internal pipes at a constant level. The construction may be such as to provide an annular space 25 between the casing 13 and the insulation 18 in which air or other inert gas under pressure above atmospheric may be maintained when the system is completed. This pressure will prevent the leaking of the water into the casing 13 and will maintain the insulation 18 in a dry atmosphere as well as provide a non-corrosive atmosphere for the rollers 24, the interior of casing 13 and the exterior of casing 17. If the structure and use is such as not to involve danger of leakage through the casing, a partial vacuum, instead of pressure, could be applied in the space 25, and it would reduce heat loss. Insulation blocks 26 of extremely low thermal conductivity, such as Johns Manville's MIN-K (siliceous material with a resin binder) or the like, may be mounted in back of each roller unit 21.

Inside of the jacket line 17, there is an axially extending conveying line 27 for passage of the molten sulfur or other hot liquid to be transported. It, too, may be made from a high tensile steel having a yield strength of 25,000 to 90,000 p.s.i. It may be of such diameter as to provide a space 28 between it and jacket line 17 for the circulation of a hot fluid of high heat capacity per unit of volume, such as hot water or hot mineral oil, to maintain the material being conveyed through line 27 in a readily flowable state. In order to control buckling under compression, pins 29 may be welded or otherwise fastened to the outer periphery of line 27 at periodic intervals along its axial length. Where the space between the lines 17 and 27 can be sufficiently small, the pins are not required.

When hot water is employed within the annular space 28, it must be highly treated in order to prevent the formation of scale and corrosion and, therefore, is preferably recirculated with the addition thereto of any required make-up water of suitable purity. Accordingly, a return pipe 30 having a protective anti-corrosion exterior shell 31 may be attached on one side of the casing 13 for the recirculation of the heated and treated water. Another pipe 32 having a similar coating 31 may be attached on the other side of casing 13 for the supply of utility and boiler feed water to the mining platform. This pipe may be protected from internal corrosion by means of a cement or other suitable lining 33. These two pipelines 30 and 32 may be attached to the casing 13 by yoke members or bands 34 at periodic intervals along the system and straps 35 may be employed to bind the lines 30 and 32 to the casing 13.

Successive sections of the casing 13 and of lines 30 and 32 may be welded or otherwise attached together on shore. Before the jacket line 17 and the inner line 27 have been introduced into the casing 13, the leading section of the latter and of the lines 30 and 32, at the forward closed ends thereof, may be attached to a vessel and as the succeeding sections are welded to the shore ends, the three lines may be pulled seaward toward the sea platform at the sulfur dome.

With reference to FIGS. 4 and 5, when the leading end of the casing 13, to which an hermetically sealed chamber 34 has been attached, has reached a point shoreward from the sea platform a distance equal to from about one half up to the whole of the expected thermal growth of the casing 13 during normal use, a prestressing apparatus may be connected to it. Accordingly, the closed end 35 of chamber 34 may support a plurality of rigid brackets 36 to which brackets 37 may be fixed. The brackets 37 may have journal sheaves 38 for the reception of chains 39. Pipes 40 may extend vertically upwardly from the brackets 37 acting as chain guides. These chain guides 40 may extend to the surface of the water and through a jack station 41. The upper ends of the guides 40 may be designed to utilize crabfoot locks 42 for cooperation with links of the chains 39 to maintain each chain taut (FIG. 6).

The jack station or platform 41 may include a base

that is secured by piling driven into the sea bottom. Guide braces 43 may be constructed on the platform 41 in lines parallel with the axis of the casing 13, and they may support sliding guide members 44 forming part of a traveling carriage 45. Locking clamps may be employed with the guide members 44 to lock the carriage 45 at different points along the braces 43.

The carriage 45 may include a base plate 46 through which the chain guides 40 extend, and to which said guides are rigidly fixed. The plate 46 may support hydraulic jacks 47 and 48 on the top of which spaced cross beams 49 may be fixed. The spacing of these cross beams 49 may be such as to freely pass the chains 39 between them, and to permit locking the chains to the cross beams by crabfoot locks 50.

The ends of the chains 39 opposite those on the platform 41 may be attached to piles 51 driven into the sea bottom, seaward of the mining station and in line with the axis of the casing 13, forming an anchoring arrangement. With the shore end of the casing 13 securely anchored, and by locking a chain 39 to the cross beams 49 as shown, application of hydraulic pressure to the jacks 47 and 48 will apply a tensile strain to the casing 13. The force producing this strain has a vertical component that is resisted by the chain guides 40. Locking the jacked chain 39 to the top of its guide 49 by a lock 42 as well as locking the carriage 45 to the braces 43 will permit descent of the jacks 47 and 48 for attachment to another chain 39 as previously described. In this way, the carriage 45 is moved seaward toward the mining location along the braces 43 while applying a tensile stress to the casing 13.

The amount of stretch of casing 13 can be such as to apply a tensile strain to the casing of an amount equal to the thermal growth of the casing 13 during normal use. In this way, the casing 13 during use will receive its prestress and eliminate the need of expansion joints between succeeding sections of the casing 13. Compressive forces will be eliminated also by this condition.

After the casing 13 has been pre-stressed the desired amount, the trench or channel 11 may be back filled. When the back fill has developed sufficient shearing strength, the temporary anchors including the shore anchor and chains 39 may be removed from the ends of the casing 13, the back fill maintaining the casing 13 in its prestressed condition.

Succeeding sections of the sulfur line 27 and hot water line 17 may be assembled and welded, respectively, together and rolled seaward from shore through the casing 13, the roller units 21 making this movement possible. The lines 17 and 27 may extend seaward to a point short of the end of the prestressed casing 13 an amount such that they, too, may be prestressed prior to final completion of the composite line. The method of pre-stressing lines 17 and 27, however, may be done by circulating hot water through them at a predetermined temperature depending upon the prestress desired. Under an alternative procedure, units of random length are completely assembled on shore and the whole multi-pipe section composed of lines 13, 17, 27, 30 and 32 pulled seaward as the lines are assembled.

Should it be desired to operate these lines or either of them in tension at all times, say, to prevent buckling or kinking, they or it may either be heated to a temperature slightly in excess of that during normal operation, or pulled, and while heated, or pulled, they or it may be welded to the outer casing 13 to retain them or it in a prestressed condition when cool. On the other hand, should it be desired to operate these lines or either of them in some compression, they or it may be heated to a temperature below the normal operating temperature. In the particular embodiment disclosed, the inner lines 17 and 27 were heated to 200° F. by passing hot water through them, causing them to expand in the neighborhood of about thirty feet. While in this expanded con-

dition, lines 17 and 27 were welded to the outer casing 13. Under these conditions, when the inner lines are placed in operation at a temperature in the neighborhood of 300° F., they will go into compression to about one-third of their yield strength. Should the lines 17 and 27 again cool down to ambient temperature, they will go into tension. If inner pipes 17 and 27 were not prestressed then they would operate solely under compression, but under this provision material of very high yield strength would have to be used.

From the foregoing it is evident that during normal operation substantially no stress from thermal causes occurs in the casing 13 and substantially no relative movement occurs between the inner lines 17 and 27 on the one hand and casing 13 on the other hand. Additionally, by employing the previously described prestressing method, these results can be accomplished without employing expansion joints within the lines.

Referring again to FIGS. 4, 5 and 6, the chamber 34 at the seaward end of casing 13 may be provided with an opening in its end wall through which the casing 13, and its enclosed hot water line 17 and sulfur line 27, may pass and be hermetically sealed to the walls of said opening. The composite line including casing 13 may extend vertically upwardly along side of the chain guides 49 and the lines 30 and 32, all of which may be encased within a casing 52. These lines may extend to the top of the jacking platform 41.

From the jacking platform 41 (not shown in FIG. 1), the composite line including casing 13, lines 17 and 27 may extend to a mining platform 53 adjacent station 41 and located over or near a sulfur dome. The platform 53 may support all of the mining equipment necessary to a self-sustaining operation. It may include a boiler 54, the feed water of which may be supplied from the line 32. A branch 55 leading from line 32 may supply utility water for the crew living on the platform 53.

As previously described, the highly treated, non-scale and non-corrosion producing water for maintaining the sulfur molten throughout the extent of the sulfur line 27 preferably should be recirculated. Accordingly, the line 30 may have therein a circulating pump 56 on the platform (or a pump on shore). This pump 56 forces the water through a heat exchange unit 57 heated by the boiler 54. The outlet 58 of the unit 57 is connected to the seaward end of line 17. The shore end of line 17 connects into line 30 which may contain a pump 59. An inlet line 60 with a check valve 61 therein may be connected to line 30 for supplying treated water from a source (not shown) to make up any losses within the system.

The sulfur line 27 may extend along the platform 53 and is connected into a vertically extending pipe 62 that leads from the sulfur bearing formation. Sea water may be pumped into a heat exchanger 63 capable of handling such water, the exchanger being supplied with heat from boiler 54. Suitable pressure pumps and other conventional sulfur mining equipment are employed to force the sea water at a temperature of about 320° F. downwardly through pipe 62, causing it to melt the solid sulfur within the mine and to force it upwardly through the sulfur line 27, thence with the aid of the pump 64, through the composite buried pipe system including casing 13 and hot water line 17 to a receiver 65 at the shore installation, which receiver can be an insulated sulfur barge.

Although the various features of the method of, and apparatus for mining a solid material and transporting it in liquid form have been described in detail to disclose fully one embodiment of the invention, it will be evident that changes may be made in such details and certain features may be employed without others without departing from the principles of the invention.

We claim:

1. A composite piping arrangement for conveying hot liquid material long distances which comprises a central pipe for conveying the hot liquid, an insulated heating

line larger than and surrounding but unattached to said central pipe through which hot fluid can be circulated to maintain the hot condition of the liquid in said central pipe, an outside jacket casing surrounding said heating line and spaced therefrom, anti-friction supporting means mounted along and around said insulated heating line at intervals substantially throughout its length to support and permit longitudinal movement of the central pipe and heating line as a unit inside said outside casing, said central pipe and heating line being attached to said jacket casing only at the extreme ends of said casing, and said central pipe and heating line being prestressed so that they are under substantial compression at their normal temperature of operation.

2. The composite piping arrangement of claim 1 where-in the anti-friction means are rollers mounted in housings, which housings are separated from the central pipe line by rigid insulation serving also to support said pipe line, the remainder of the insulation being non-rigid insulation of high efficiency.

3. A composite pipeline for conveying molten material that is solid in its natural state and capable of being melted by the application of heat, said pipeline being designed to convey said molten material for a distance of several miles in a straight line without the use of any expansion joints, said pipeline comprising lengths of pipe joined end to end to form a continuous outer casing, and an inner assembly with the inner assembly being attached to the outer casing only at the extreme ends of the entire pipeline and said assembly being otherwise freely movable inside and longitudinally of said outer casing, said inner assembly comprising lengths of pipe joined end to end to form a central pipe for conveying the molten material and being slidably supported inside a second pipe similarly made up of lengths of pipe joined end to end, said second pipe being of larger diameter than said central pipe to provide a space therebetween for the passage of a heating liquid, said second pipe of said assembly being surrounded with heat insulating material in which are supported at intervals throughout its length insulated roller means for permitting free longitudinal movement of said entire inner assembly inside said outer casing, said outer casing being held under substantial tension at ambient temperatures, means for pumping molten material through said central pipe, and means for flowing a heating liquid through the space between said central pipe and said second pipe in the same direction as the flow of said molten material through said central pipe.

4. A composite pipeline as defined in claim 3 in which a return pipe for the heating liquid is attached to the outside of the outer casing and connected at the ends of the pipeline to the space between the central pipe and the

second pipe to provide a closed circuit for continuously circulating said heating liquid.

5. A composite pipeline for transporting a hot liquid for a distance of several miles while maintaining the temperature thereof substantially above the ambient temperature which comprises, an outer casing extending in a substantially straight line, an insulated assembly of pipes inside said outer casing and spaced therefrom, one pipe of the assembly carrying the hot liquid and another pipe of the assembly carrying an auxiliary heating fluid, said insulated assembly of pipes except at the ends of the pipeline being supported on anti-friction means inside said outer casing and completely free to move longitudinally relative to each other and relative to the outer casing, said inner assembly of pipes being anchored only at each end of the pipeline to the outer casing after being expanded to a length about 50% to 70% of the total length to which such assembly would normally expand when heated to the temperature at which the hot liquid is transported, whereby said inner assembly is under substantial compression when the pipeline is transporting the hot liquid and is under substantial tension when the pipeline is cooled to or near the ambient temperature, and whereby said inner assembly of pipes can be readily cut free to relieve stresses whenever the pipeline is cooled to ambient temperatures.

6. A composite pipeline as defined in claim 5 in which the outer casing is prestressed in tension and buried in soil before the inner assembly of pipes is stressed or heated to the temperature at which the hot liquid is transported.
